CLAIM

We claim the ornamental design for a container with closure, as shown and described.

DESCRIPTION

FIG. 1 is a top, front, left side perspective view of a container with closure showing our new design;

FIG. 2 is a front elevation view thereof, the rear elevation view being a mirror image;

FIG. 3 is a right side elevation view thereof;

FIG. 4 is a rear elevation view thereof;

FIG. 5 is a top plan view thereof; and,

FIG. 6 is a bottom plan view thereof.

The broken lines shown in the drawings are for illustrative purposes only and form no part of the claimed design.
